JOSEPH V. HARTMAN, OF MARATHON, OHIO.

Letters Patent No 63,632, dated April 9, 1867.

IMPROVEMENT IN CHURN POWER.

The Schedule referred to in these Letters Patent and making part of the same.

TO ALL WHOM IT MAY CONCERN:

Be it known that I, JOSEPH V. HARTMAN, of Marathon, Clermont county, and State of Ohio, have invented a new and improved Pendulum Churn Power, of which the following is a full and clear description thereof, reference being had to the accompanying drawings, making a part of this specification.

My improvement relates to a system of levers to which motion is communicated by clock-work, the levers being in connection with churn dasher, cause them to pass back and forth in the body of the churn.

Figure 1 represents a perspective view of my improved pendulum churn power applied to a churn with two dasher.

Figure 2 is a front elevation of the same, with a vertical section of the body of the churn.

A is a weight, attached to cord *a*, which is coiled about the drum *b*. The drum *b* is journalled in the frame *B*. Upon the axle of the drum *b* is secured the gear-wheel *c*, meshing into the pinion *d*. The axle of pinion *d* is continued without the frame *B*, and bears upon its extreme outer end the ratchet-wheel *e*. To the verge *f*, which engages the ratchet-wheel *e*, is secured the check-bar *g*. It passes down by the side of the pendulum *C*, which loosely clasps it near its middle point, *h*. At a suitable distance below the point of suspension of the pendulum *C*, a bar, *D*, is secured to the pendulum in a transverse position to it. To the extreme ends of bar *D* are pivoted links *E E'*. The lower ends of these links are pivoted to the short levers *F F'*. The levers *F F'* are pivoted to the frame *B* at *i i*. The dash handles *G G'* are pivoted to the inner or short arms of the levers *F F'* at *k*.

To operate the churn, the weight *A* is wound up and the pendulum set in motion, the same as in an ordinary clock. The bar *D* has, first, one of its extreme ends elevated, as shown in fig. 2. The inner end of the lever, beneath the elevated end of bar *D*, is depressed, and the dash connected with it reaches its lowest position in the body of the churn; in the mean time the other dash has been elevated to its greatest height. This vibration of the bar *D* gives a reciprocating motion to the churn-dashes through the system of links *E E'* and levers *F F'*. The length of time employed in churning will depend upon the position of the fulcra *i i* of the levers *F F'*.

Having fully described the construction and operation of my improved pendulum churn power, I make the following claim, which I desire to secure by Letters Patent:

The dash handles *G G'*, levers *F F'*, links *E E'*, bar *D*, and pendulum *C*, arranged and operated as above described and for the purpose set forth.

J. V. HARTMAN.
